Primary Examiner—Louis Zarfas*Assistant Examiner*—Mark Cavanna(74) *Attorney, Agent, or Firm*—Quarles & Brady LLP(57) **CLAIM**

The ornamental design for a faucet, as shown and described.

DESCRIPTION

In a preferred embodiment, the nature of this product is as a plumbing fitting in the form of a faucet used to wash various items and/or body parts.

FIG. 1 is a left, top, front perspective view of a faucet embodying my new design;

FIG. 2 is a left side elevational view thereof;

FIG. 3 is a right side elevational view thereof;

FIG. 4 is a front elevational view thereof;

FIG. 5 is a rear elevational view thereof;

FIG. 6 is a top plan view thereof;

FIG. 7 is a bottom plan view thereof;

FIG. 8 is a left, top, front perspective view of a faucet according to another embodiment of my new design;

FIG. 9 is a left side elevational view thereof, the right side elevational view thereof being a mirror image of the left side shown;

FIG. 10 is a front elevational view thereof;

FIG. 11 is a rear elevational view thereof;

FIG. 12 is a top plan view thereof; and,

FIG. 13 is a bottom plan view thereof.

The broken lines are included for the purpose of illustrating portions of the faucet that form no part of the claimed design.
